UNITED STATES PATENT OFFICE.

SHIRO KONDOW, OF LOS ANGELES, CALIFORNIA.

DESIGN FOR A CHARM, STICK-PIN, STATUETTE, LUCKY DOG, OR COMIC DOG.

48,002.

Specification for Design.

Patented Oct. 19, 1915.

Application filed June 21, 1915. Serial No. 35,457. Term of patent 3½ years.

To all whom it may concern:

Be it known that I, SHIRO KONDOW, a subject of the Emperor of Japan, residing at the city of Los Angeles, in the county of Los Angeles and State of California, have invented a new, original, and ornamental Design for a Charm, Stick-Pin, Statuette, Lucky Dog, or Comic Dog, of which the following is a specification, reference being had to the accompanying drawings, forming part thereof.

In the drawings, Figure 1 is a front elevation of a watch charm, showing my new design, and Fig. 2 is a side elevation thereof.

I claim:

The ornamental design for a charm, stick pin, statuette lucky dog or comic dog, as shown.

SHIRO KONDOW.
